United States Patent Office

Des. 203,266
Patented Dec. 21, 1965

203,266

BRICK

Michael Pascucci, 5 Bruce Lane, Manhasset, N.Y.

Filed July 6, 1964, Ser. No. 80,728

Term of patent 14 years

(Cl. D18—2)

FIG. 1.

FIG. 2.

FIG. 3.

FIG. 1 is a side perspective view of a brick, showing my new design;

FIG. 2 is a side elevational view thereof; and

FIG. 3 is an end elevational view thereof.

The side and end not shown has substantially the same appearance as the side and end shown.

I claim:

The ornamental design for a brick, as shown and described.
